UNITED STATES PATENT OFFICE.

GEORGE E. BAIRD, OF CHICAGO, ASSIGNOR OF ONE-HALF TO WILLIAM D. HENKEE AND ANDREW REINER, OF BLUE ISLAND, ILLINOIS.

CLOSED-CONDUIT ELECTRIC RAILWAY.

SPECIFICATION forming part of Letters Patent No. 538,650, dated May 7, 1895.

Application filed June 11, 1894. Serial No. 514,198. (No model.)

To all whom it may concern:

Be it known that I, GEORGE E. BAIRD, a citizen of the United States of America, residing at Chicago, in the county of Cook and State of Illinois, have invented certain new and useful Improvements in Closed-Conduit Electric Railways, of which the following is a specification.

My invention relates to improvements in electric railways of that class in which the motors that propel the cars receive their current through a conductor lying in a conduit which runs along the car-track.

The invention is fully described and explained in this specification and shown in the accompanying drawings, in which—

Figure 1 is a view, partly in longitudinal vertical section and partly in side elevation, showing a conduit provided with the conductors forming part of my invention and the contact-making bar dependent from a car. Fig. 2 is a similar enlarged view of the same elements shown in Fig. 1. Fig. 3 is a top plan of the parts shown in Fig. 2. Fig. 4 is a top plan of the conductors and their movable contact-levers, the top of the box containing the levers being removed and certain parts shown in section. Fig. 5 is a transverse vertical section through the line 5 5, Fig. 4, the view being in the direction indicated by the arrow *a*, Fig. 4. Fig. 6 is a transverse vertical section through the line 6 6, Fig. 2, the view being in the direction indicated by the arrow *a'*, Fig. 2.

In the views, A is a conduit of suitable form, preferably provided with ribs, A', and having the usual upwardly open longitudinal slot bounded by slot-rails, A². Near the bottom of the conduit are suitably supported parallel lines of pipe-sections, B, B', and at suitable intervals two part boxes, C, C', are set in the lines of sections and receive the ends thereof, the ends of the pipes being screwed or otherwise set into the boxes. Conducting wires, W, W', connected with a dynamo or other source of electrical supply are inclosed in the pipes, B, B', and pass through the compartments, C, C', respectively, of the boxes, one being the supply and the other the return wire of the system. Each of the wires, W, W', has attached to it, at a suitable point in

each of the boxes, C, C', two brushes, *b* or *b'*, preferably of spring metal and curved outward at their upper ends as shown in Fig. 5. In the walls of each of the boxes are journaled two hollow transverse shafts, D, D', Figs. 2, 4 and 5, and on the outer ends of these shafts respectively are rigidly mounted hollow rocking levers, E, E', bearing contact rollers, R, R', of conducting material. On the inner ends of the shafts, D, D', are mounted hollow rocking levers, F, F', weighted at one end as shown in Fig. 2 and terminating at their opposite ends in contact blocks, *f*, *f'*, normally held above the brushes *b*, *b'*, but adapted to be depressed so as to make contact therewith. Wires, *w*, *w'*, connect the contact blocks, *f*, *f'*, respectively, with the contact rollers, R, R'.

The conduit, A, lies preferably between the rails of an ordinary car-track adapted to support wheeled cars of ordinary construction, any or all the cars being provided with suitable electric motors for their propulsion. Each motor-car is provided with a dependent hollow arm, G, Figs. 1, 2, 3, and 6, extending downward through the slot between the rails, A², A², and moving freely along the conduit, and this arm supports a transverse bar, G', to whose ends are fastened two parallel contact-bars, H, H', of suitable conducting metal. The ends of the two contact-bars are connected by transverse bars *h* and are provided with horizontal rollers, R², R², Figs. 2, 3, and 6, which bear against longitudinal guide-rails, A³, A³, and thus regulate the position of the contact-bars, H, H'. The ends of each of the contact-bars, H, H', have their lower edges curved upward as shown in Fig. 2, and are of non-conducting material, the length of the conducting bar in each being such however as to cover the space between any two contiguous contact-rollers, R, R, or R', R', and thus insure contact of each conducting-bar at all times with at least one of said rollers.

The bars, H, H', are in the vertical planes of the rollers, R, R', respectively, at such a height that as they pass along the conduit and come into contact with the rollers, the latter are depressed and the blocks, *f*, *f'*, are brought into contact with the brushes, *b*, *b'*, respectively. Wires, *w*², *w*², extend from the bars, H, H', to the motor in the car above, and

since each of the bars, H, H', always holds one of the corresponding rollers, R, or R', in its lowest position, the wires, W, W', are constantly in electrical connection and a current 5 passes constantly through the two wires and the motor. This current may of course be interrupted by means of a switch in either of the wires, w^2 , w^3 , or by any other means under the control of the operator of the car.

10 The lower edges of the ends of the bars, H, H', are curved upward in order to avoid shock as the bars make or break contact with rollers, R, R', and they are formed of non-conducting material in order to avoid sparking 15 as the blocks, f, f', break contact with the brushes, b, b'. The parts of the supply and return wires, W, W', lying within the pipes, B, B', may be insulated in any desired manner, as by wrapping with any suitable substance 20 or by embedding them in some non-conducting substance with which the pipes are filled. Those parts of the wires lying within the compartments, C, C', may also be insulated, if desired, except at their points of 25 contact with the brushes, b, b'.

It is evident that the form and arrangement of the brushes, b, b', is not essential; it being only necessary to provide suitable contact surfaces connected with the wires and adapted 30 to receive the contact of the blocks, f, f', for the purpose of closing a circuit. The form shown is desirable, however, as affording certain and effective contacts.

The contact-making devices arranged along 35 the wires, W, W', are shown and described as placed in two-part boxes and this is a convenient and practical construction. It is evident, however, that, if desired, the box may contain but a single chamber inclosing two 40 contact-devices, or that the two chambers instead of being inclosed within a single wall or box may be wholly separate from and independent of each other. In any case each of the chambers may be made water-tight and 45 the joint about the rocking shaft D or D' may be provided with some simple packing sufficient to exclude moisture, thus enabling the system to work practically in a temporarily flooded conduit, or any other situation, in 50 which complete isolation of the conducting wires is necessary to guard them against moisture.

It is evident that certain details of construction shown and described herein are applicable to a single wire system in which the return is through one of the track wires in 55 electrical connection with the motor.

Having now described and explained my invention, what I claim as new, and desire to secure by Letters Patent, is—

1. The combination with a track and a car moving thereon and provided with a suitable motor, of the arm, G, dependent from the car, the parallel contact bars, H, H', supported by said arm, the lines of pipe sections, B, B', and 65 chambers, C, C', and conducting wires, W, W', lying within said pipe section and chambers, respectively, and insulated except at points of exposure within the chambers, the contact brushes, b, b', attached to said wires, the oscillating levers, F, F', provided with the contact blocks, f, f', adapted to be brought into contact with the brushes, b, b', and members attached to the levers, F, F', and lying outside the chambers, C, C', said members being 70 adapted to be actuated by the contact bars, H, H', respectively, as the car moves along the track, whereby the wires, W, W', may be brought into electrical connection with the motor. 75

2. The combination with the track and the car moving thereon and provided with a suitable electric motor, of the arm, G, dependent from the car, the transverse bar, G', supported by the arm, the contact bars, H, H', supported 80 by the bar, G', and spaced with reference to each other by the transverse bars h, the suitably supported lines of pipe sections, B, B', and chambers, C, C', the conducting wires, W, W', inclosed in said pipe sections and chambers and insulated except at points of exposure within said chambers, the contact levers lying within the chambers and adapted to make electrical contacts with said wires, and levers lying outside the chambers and connected with said contact levers, the contact bars, H, H', being adapted to actuate in succession the contact devices of said lines respectively, as the car moves along the track, whereby a circuit may be closed to said wires 85 and said motor. 90

3. The combination with the conduit provided with the guide rails, A³, A³, the two suitably insulated conductors lying therein and the two sets of contact devices connected with 105 said conductors respectively of the dependent arm, G, the parallel contact bars, H, H', supported by the arm and spaced with reference to each other and the rollers, R², R², mounted on said contact bars and adapted to impinge 110 upon said guide rails and regulate the lateral position of said contact bars thereby insuring the actuation of said contact devices by the bars respectively, substantially as shown and described.

GEORGE E. BAIRD.
